CLAIM

The ornamental design for a foot massage device, as shown and described.

DESCRIPTION

FIG. 1 is a front plan view of a foot massage device, with a stabilizing base with legs closed;

FIG. 2 is a back plan view of the foot massage device, with a stabilizing base with legs closed;

FIG. 3 is a top plan view of the foot massage device, with a stabilizing base with legs closed;

FIG. 4 is a right plan view of the foot massage device, with a stabilizing base with legs closed;

FIG. 5 is a left plan view of the foot massage device, with a stabilizing base with legs closed;

FIG. 6 is a bottom plan view of the foot massage device, with a stabilizing base with legs closed;

FIG. 7 is an upper left rear perspective view of the foot massage device, with a stabilizing base with legs closed;

FIG. 8 is an upper right front perspective view of the foot massage device, with a stabilizing base with legs closed;

FIG. 9 is a front plan view of the foot massage device, with a stabilizing base with legs open;

FIG. 10 is a back plan view of the foot massage device, with a stabilizing base with legs open;

FIG. 11 is a top plan view of the foot massage device, with a stabilizing base with legs open;

FIG. 12 is a right plan view of the foot massage device, with a stabilizing base with legs open;

FIG. 13 is a left plan view of the foot massage device, with a stabilizing base with legs open;

FIG. 14 is a bottom plan view of the foot massage device, with a stabilizing base with legs open; and,

FIG. 15 is an upper right front perspective view of the foot massage device with legs open.

(Continued)

The broken lines shown in FIG. 8 are for the purpose of illustrating environmental structure, which form no part of the claimed design.
